MATHIAS ODIN SEVERIN MADSEN, OF AARHUS, DENMARK, ASSIGNOR TO OTTO KRISTIAN HEESCH, OF AARHUS, DENMARK.

COIN-CONTROLLED APPARATUS.

Application filed April 30, 1921. Serial No. 465,914.

To all whom it may concern:

Be it known that I, MATHIAS ODIN SEVERIN MADSEN, a subject of the King of Denmark, residing at Aarhus, Denmark, have invented certain new and useful Improvements in Coin-Controlled Apparatus, of which the following is a specification.

This invention relates to coin controlled apparatus, and particularly to prepayment 10 meters for the supply of gas, electricity, or the like, or the maintenance in operation of an economiser clock for electric staircase lighting or the like.

One object of the invention is to provide 15 a simple and effective automatic mechanism in apparatus of the class mentioned for discontinuing the supply or stopping the clock-work when the amount of commodity paid for has been supplied.

20 Another object of the invention is to provide a discontinuing mechanism in which any desired number of coins up to a predetermined maximum can be inserted in succession at one time, or a single coin.

25 A further object of the invention is to provide a discontinuing mechanism that can be used with any kind of clockwork with only trifling constructional alteration of the latter.

30 In the accompanying drawing a constructional form of the invention is shown by way of example, operatively combined with the works of a common alarm clock. In these drawings—

35 Figure 1 is a side elevation of the device; Figure 2 is a top view of the same device; Figure 3 is an elevation of the same as seen from the left side in Fig. 1.

40 A is a bracket plate fitted to the frame plate *a* of the clock and secured thereto by means of a pair of screws *b*, and *B* is a similar plate secured by suitable means to the casing, not shown, which encloses the clock and the automatic device, which device is assembled on and between the two 45 said plates *A* and *B*.

The device comprises a shaft *C*, which is revolvably but not slidably journalled in bearings in the plates *A* and *B*, and the 50 outer end thereof passes through a wall in the afore-mentioned casing and has, on the outside, a crank handle *D* fitted thereto. The part of shaft *C*, which is located between the plates *A* and *B* is made of a somewhat larger diameter than its other part and

has on the greater part of its length a screw thread for a nut *E* screwed thereon. Outside of the plate *B* a ring-shaped disc *F* is secured to the shaft *C* by means of a set screw *c*, and outside of said disc *F* is fitted, 60 loose on the shaft *C*, a ratchet wheel *G*, which latter is coupled to the disc *F* by means of a pin *d*, Figure 3, engaging an arc shaped slot *e* in the ratchet wheel. The pin *d* is attached to one end of a coiled spring *f*, 65 the other end of which is attached to a pin *g* secured on the ratchet wheel. By this arrangement there is a certain movement between the ratchet wheel *G* and the disc *F*, and, consequently also between the ratchet 70 wheel and the shaft *C*, whilst the spring *f* tends to hold the ratchet wheel and the disc at a given angular position relatively to each other.

A little farther inside of the plate *B* is 75 revolvably but not slidably fitted to shaft *C* a gear wheel *H*, into which two pins *h* are fitted diametrically opposite to each other these pins *h*, being disposed parallel to the shaft *C* and each passing loosely through a 80 separate hole in the nut *E*, so that the latter is turned when the gear wheel *H* turns. The nut *E* is made comparatively wide and has in its periphery a groove, into which is fitted a revolute ring *k*, into which is secured a radially projecting pin *l* which passes through a hole in a flat bar *K* close to an end thereof. This bar passes loosely through and is guided in a hole in the upper part of the plate *A* and a hole in one arm of 85 an angle plate *l'* carried by said plate *A*. The ring *k*, therefore does not take part in the rotation of the nut *E*, but the axial movement of the nut will be transmitted to the bar *K* by means of the pin *l* in said ring. 90

The ratchet wheel *G* co-operates with a pawl *L* under action of a spring *m*, the said pawl being revolvably fitted, by means of a screw pin *n*, to the outer side of the plate *B*. On the outer side of the ratchet 100 wheel *G* and close to its periphery a pin *o* is fitted. The pawl is made of a special shape so that it acts with the teeth in the ratchet wheel for preventing the latter from reversing, and against the pin *o*. For 105 this purpose the pawl is provided with an extension, which lies along the side of the ratchet wheel, and which terminates in a hook *p*, which will catch and seize the pin *o*, and thereby positively lock the ratchet 110

wheel, which turns in the direction indicated by the arrow in Figure 3. In order that the pawl can unpreventedly assume such position, that the hook *p* catches the pin *o*, one tooth is omitted at a given point in its periphery so that an empty space is there produced, into which the pawl moves when the hook shall seize the pin *o*. When the ratchet wheel has, by this seizing of pin *o* been locked, the disc *F*, which is under action of spring *f*, will be in such a position that a pocket *q*, provided in the periphery of the disc and closed at the sides and turning inwardly from the periphery will be just beneath the opening *r* through which the coin is inserted.

The gear wheel *H* co-operates with a pawl, which consists of a thin strip *M* of metal placed on edge and fitted to the upper end of a small slide *N*. The latter is fitted to slide up and down on a flange of the plate *A*, being guided by a pair of screw pins *s*, which pass through a longitudinal slot *t* in the slide, Figure 3. At its lower extremity the side *N* has a foot *u* extending to one side. A coiled spring *v*, the upper end of which is attached to the slide *N* whilst its lower end is attached to the plate *A*, pulls the slide *N* and with it the pawl *M* towards their lowermost position, in which the pawl is disengaged from the gear wheel *H*. *O* is a wheel of the clock work, upon which are fitted any desired number of pins *y*, which, upon the rotation of the wheel will lift the slide *N* by acting from below against its said foot *u*, and the arrangement is such that the lift which each pin *y* gives to the slide at the rotation of the wheel, causes the pawl *M* to turn the gear wheel *H* by one tooth, whereupon the spring *v* will again pull the slide *N* with the pawl *M* down into a position, in which the slide will remain until the following pin *y* begins to act against the foot *u*.

45 The dog pin *h* has the effect that the rotation of the gear wheel *H* thus produced is transmitted to the nut *E*. A reversing of the gear wheel *H* is prevented by a flat spring *w* acting as a pawl, Figures 1 and 2, which 50 at the same time produces a sufficient friction so as to prevent the gear wheel from turning when the shaft *C* is turned by the crank handle *D*. In an arm 2 of the plate *A* is journalled a swinging lever *P*, which 55 has one curved or bent arm 3, the outer end of which extends into the path of the bar *K* as shown in Fig. 1. A cross piece 4, (Figure 2), on the lever *P* carries an arm 5, (Figures 1 and 2), and the outer end 6 of 60 this arm 5 forms a locking member, which, in the constructional form shown, co-operates with the balance wheel 7 of the clock, to arrest said wheel and to release same. A spring 8 tends to hold the lever *P* in the 65 position shown in Figure 1 in which the end

6 does not interfere with the operation of the clockwork. Turning in this direction beyond a certain limit is prevented by a stop, not shown.

The operation is as follows: Assuming 70 that the mechanism is in its normal position, in which the pawl *L* holds the ratchet wheel *G* by the hook engaging the pin *o*, and that the nut *E* is in its outermost position to the right in Figure 1, the pocket *q* in disc *F* is 75 immediately beneath the coin insertion slot *r*, and its pin *d* is in the position in the slots in the ratchet wheel, Figure 3. If, now, a coin of the necessary size (face value) is dropped into the slot, it will enter the pocket 80 *q*, projecting a little therefrom. Thereupon the shaft *C* and the thereto fitted disc *F* is, by aid of the crank handle *D*, turned to the right (in the direction indicated by the arrow in Figure 3) whilst the ratchet wheel remains for a while still, being held by the pawl, which is possible because the pin *d* is 85 moving in the slot *e*, and during this first movement the coin will press against the pawl and turn the latter in such a manner, that 90 its hook *p* is disengaged from the pin *o* when the pin *d* reaches the other end of the slot *e*. The turning of shaft *C* may, therefore, be continued, whilst now the ratchet wheel *G* turns with it, and the coin drops 95 from the pocket *q* into a collector or the like. When, however, a complete revolution has been made, the hook *p* of the ratchet will again engage the pin *o* and lock the ratchet wheel, whereby a further turning of the 100 shaft in the said direction is prevented. If, now, the crank handle is released, the spring *f* will cause the disc *F*, and therewith also the shaft *C* to turn so far back that the pin *d* again comes into the position in the slot *e* 105 shown in Figure 3, corresponding to which the pocket *q* is again immediately beneath the coin insertion slot *r*. The shaft *C* may, thus, after each insertion of a coin, be turned through one revolution, and is, in fact, 110 turned a little beyond one revolution, but is subsequently returned automatically by this distance. The gear wheel *H* and with it the nut *E* is by means of the spring *z* acting as a pawl prevented from taking part 115 in this revolution of the shaft *C*, and therefore the nut and with it also the bar *K* are shifted a certain distance to the left (Figure 1). These operations may, obviously, 120 be repeated several times after each other 120 as long as the travel of the nut *E* on the screw threaded part of the shaft *C* allows, the said nut being at each insertion of a coin, moved by the length of the pitch of the screw to the left, and thereby the outer end of the bar *K* being removed more and more from the position, in which it, by acting on the arm 3 of the lever *P* induces the locking member 6 to stop the clock work, 125 by engaging the pin or stop on the wheel 7. 130

When the clockwork has run for a predetermined period, one of the pins γ on the wheel O will arrive under the heel u of the slide N and further advance of the wheel

- 5 will be attended by upward travel of the slide and consequently of the pawl bar M , which will return the gear wheel H to the extent of one step or tooth pitch and with it the nut E (turning is in the same direction as the shaft C has been turned by the crank handle D); whilst the shaft stands still, the nut E is moved to the right (Figure 1) on the shaft, and carries the bar K with it by aid of the ring k and its pin l .
- 10 When the bar K has, by such means, been advanced sufficiently far, its outer end acts on the arm 3 of the lever P and, at its further advance, turns this lever until the locking member 6 stops the clockwork.
- 15

- 20 The time, therefore, which will be required for moving the bar K in the direction towards the lever P by a distance which is equal to that by which the bar is moved away from the lever after the insertion of a coin or of several coins in succession, is, absolutely determined by the number of teeth in the gear wheel H , the number of pins γ in the wheel O and the speed of the revolution of the latter dependent 25 on the clock work. The said time can, thus, be varied or regulated by simply varying the number of pins.

- 30 The clockwork may, of course, be kept running continuously if one or several coins are inserted before the locking member e reaches 35 its operative position.

- 35 It will be understood that the amount of gas, electricity, or other commodity delivered by a prepayment meter being proportional 40 to the travel of the clockwork of the

meter, the device described will shut off the service when the amount paid for in advance by insertion of a coin or coins has been supplied to the customer.

I claim:

1. An apparatus of the class described comprising in combination, a clockwork train, a control device which is movable away from a clockwork stopping position proportionally to the number of coins inserted in succession, coin controlled means for moving said member as aforesaid, a slide adapted to be periodically actuated by a wheel of the clockwork train, a pawl member carried by said slide, a gear adapted to be turned stepwise by said pawl, and connections between said gear and the control device for returning the latter to its clockwork stopping position.

2. An apparatus of the class described comprising in combination, a clockwork train, a screw-threaded member, a nut engaging the threads thereof, means movable by said nut for arresting the clockwork when the nut is in an end position, coin controlled driving means for turning the screw-threaded member and thereby moving the nut away from said end position proportionally to the value of coins inserted in the apparatus, a slide adapted to be periodically actuated by a wheel of the clockwork train, a pawl member carried by said slide, a gear turning loosely on the screw-threaded member and adapted to be turned stepwise by said pawl, and connections between said gear and the nut.

In testimony whereof I have affixed my signature.

MATHIAS ODIN SEVERIN MADSEN.
